COMBINED SHOE HORN AND HORN

Sam Kupperman and William McMillan, Chicago, Ill.,
assignors to R B Toy Development Co., Skokie, Ill.,
a corporation of Illinois

Filed Oct. 28, 1966, Ser. No. 4,461

Term of patent 14 years

(Cl. D86—10)

The figure is a side perspective view of a combined shoe horn and horn showing our new design, the side opposite that shown being a mirror image thereof.

We claim:

The ornamental design for a combined shoe horn and horn, as shown and described.
